UNITED STATES PATENT OFFICE.

EDWARD F. CHAFFEE, OF SYRACUSE, NEW YORK, ASSIGNOR TO THE O. M. EDWARDS COMPANY, INC., OF SYRACUSE, NEW YORK, A CORPORATION OF NEW YORK.

SASH HOLDER OR LATCH.

Application filed January 9, 1923. Serial No. 611,684.

This invention relates to window sash holders or latches such as are used to hold railway car windows in raised position, and has for its object, a sash holder which is particularly simple in construction, economical in manufacture and highly efficient and durable in use and particularly a construction by which the locking lever is rigidly supported and easily assembled in the casing.

10 The invention consists in the novel features, and in the combinations and constructions hereinafter set forth and claimed.

In describing this invention, reference is had to the accompanying drawing in which like characters designate corresponding parts in all the views.

Figure 1 is a front elevation of one form of sash holder embodying my invention. Figure 2 is a rear elevation thereof.

20 Figure 3 is a rear elevation of the casing, the lever and spring being removed.

Figure 4 is an edge view looking to the right, Fig. 1.

25 Figure 5 is a sectional view on line 5—5, Fig. 2.

Figure 6 is a front elevation of another form of such lock embodying a feature of my invention.

30 Figure 7 is a sectional view on line 7—7, Fig. 6.

This sash holder comprises generally a casing having a recess opening through its rear face and with a segmental bearing socket in the recess, and an operating angle lever having a hub at its angle mounted to rock in the socket, one arm of the lever extending outside of the casing and serving as a handle, and the other arm being movable from within the recess to the outside thereof

35 and vice versa and serving as a latch.

The lever is so mounted in the recess and the socket as to be removable and replaceable upon an axial movement of the lever through the open rear side of the casing, and the sash holder also comprises a construction and arrangement of the lever and the casing by which they normally interlock and prevent axial displacement of the lever, and by which the lever may be shifted out

45 of such interlocking relation and permit displacement of the lever when it is rocked about its axis to a predetermined abnormal position.

1 designates the casing having a recess 2

opening through its rear face, the casing being in the general form of a shallow oblong box having outwardly extending flanges 3 for lying on the face of the sash and for securing thereto by suitable means as screws extending through openings 4 in said flanges. The casing is here shown as provided with a laterally extending rigid pinch handle 5. This handle 5 is provided with a prong 6 on its inner edge which enters the window sash, and aids in securing the casing to the sash.

7 is the segmental bearing socket which is located in the lower outer corner of the recess 2, this socket being cylindrically curved.

8 is the angle lever having a hub 9 at its angle in said socket, and also having one arm 10 thereof extending to the outside of the casing through an opening 11 in the lateral side remote from the socket 7, and overlying the pinch handle 5, and serving as the handle of the lever; and having its other arm 12 movable through an opening 13 in the outer lateral side or edge of the casing from within the recess to the outside of the casing and serving as a latch to engage catches or a rack on the window guide or frame as will be understood by those skilled in the art.

One of these openings 11, 13 and usually both of them open through the rear face of the casing although it is not necessary, except to make the casing as shallow as possible, that only the opening through which the handle arm 10 extends, open through the rear face in order to permit detachment of the lever 8, by an outward axial movement of the lever out of the socket 8 through the open rear side of the casing 1.

Preferably, the lever is placeable in and removable from the recess 2 and bearing 7 by an axial movement when the lever 8 is in an abnormal position in which the latch arm 12 is located entirely within the recess 2, and the lever and casing are provided with means which normally interlock and prevent axial displacement of the lever.

As here illustrated, the casing is provided with a barrier or shoulder at the rear side of one of the openings 11, 13 which normally overlies the contiguous lever arm 10 or 12, and as seen in Figures 2, 3, the casing is formed with a barrier or shoulder 14 at the lower end of the opening 13 for the arm 12,

and the arm 12 is provided with a portion, as a tooth 15 normally located behind said barrier.

A spring usually interposed between the arm 12 and the opposite wall of the casing, acts on the lever to thrust the arm 12 outwardly. When this spring is removed, the lever arm 10 can be depressed far enough to withdraw the arm 12 entirely within the recess 2, so that the portion 15 of the lever arm 12 is out of interlocking engagement with the barrier 14 and the lever 8 can be removed axially through the open rear side of the casing 1. In assembling the reverse of this operation takes place.

Usually, the casing 1 is provided with a stud 17 arranged coaxially with the bearing socket 7, this stud projecting beyond the plane of the rear face of the casing and into a hole in the window sash. However, the hub 9 of the lever bears on the bearing face of the socket 7.

The spring 16 seats at one end in a socket 18 in one of the lateral sides or edges of the recess and at its other end surrounds a stud 19 on the arm 12 of the lever 8.

In Figs. 6 and 7 another form of sash latch having a pivoted angle lever thrusting against a segmental bearing socket, is shown. In these figures 21 designates the casing which is in the form of a base or support. 24 is the bearing socket. 25 is the angle lever having its hub 26 journaled in said socket and arms 27, 28 serving respectively as a handle, and as a latch. 29 is the spring, it being here shown as a torsion spring located in the hub 26 and coiled about a stud or rivet 30 extending axially through the hub 26 and having a head 31 overlying the outer face of the hub and holding the lever from displacement out of the recess, bearing and socket. The spring has arms 32, 33 at its ends thrusting against the casing and one arm of the lever, respectively.

In each of the forms shown in Figs. 1 to 5, and 6 and 7, the bearing socket which is of relatively large extent holds the operating lever in alinement as the hub bears on the cylindrical face of the socket throughout the length of the hub. Hence, the liability of the lever becoming loose and out of alinement under the severe usage to which these locks are subjected in their normal use, is reduced to a minimum.

What I claim is:

1. A sash holder comprising a casing having a recess opening through its rear face, and an angle lever mounted at its angle to rock in the casing and being removable and replaceable through the open rear side of the casing upon axial movement of the lever, one arm of the lever extending outside of the casing and serving as a handle and the other being movable into and out of the casing and serving as a latch, the lever nor-

mally interlocking with the casing to prevent axial displacement, substantially as and for the purpose specified.

2. A sash holder comprising a casing having a recess opening through its rear face, and an angle lever mounted at its angle to rock in the casing and being removable and replaceable through the open rear side of the casing upon axial movement of the lever, one arm of the lever extending outside of the casing and serving as a handle and the other being movable into and out of the casing and serving as a latch, the lever normally interlocking with the casing to prevent axial displacement, and being movable out of interlocking engagement with the casing when operated to withdraw the bolt into the casing, substantially as and for the purpose specified.

3. A sash holder comprising a casing having a recess opening through its rear face, a lever mounted at its angle to rock in the casing and being removable and replaceable through the open rear side of the casing upon axial movement of the lever, one arm of the lever extending outside of the casing and serving as a handle and the other being movable into and out of the casing and serving as a latch, the lever normally interlocking with the casing to prevent axial displacement, and a spring acting on the lever to normally hold the lever and casing in interlocking relation, substantially as and for the purpose described.

4. A sash holder comprising a casing having a recess opening through its rear face, an angle lever mounted at its angle to rock in the casing and being removable and replaceable through the open rear side of the casing upon axial movement of the lever, one arm of the lever extending outside of the casing and serving as a handle and the other being movable into and out of the casing and serving as a latch, the lever normally interlocking with the casing to prevent axial displacement, and being movable out of interlocking engagement with the casing when operated to withdraw the bolt into the casing, and a spring acting on the lever and tending to thrust the latch out of the casing and hold the lever in interlocking engagement with the casing, substantially as and for the purpose set forth.

5. A sash holder comprising a casing having a recess opening through its rear face and with openings in its lateral sides, one opening extending also through the rear face of the casing, and an angle lever mounted at its angle to rock in the casing and being removable and replaceable through the open rear side of the casing upon axial movement of the lever, one arm of the lever extending through one of the openings to the outside of the casing and serving as a handle, and the other arm being movable into

and out of the casing through the other opening and serving as a latch and one of said arms normally interlocking with the casing to prevent axial displacement of the lever, and being movable out of interlocking engagement when the lever is operated to withdraw the latch arm into the recess, substantially as and for the purpose specified.

- 10 6. A sash holder comprising a casing having a recess opening through its rear face and with openings in its lateral sides, one opening also extending through the rear face of the casing an angle lever mounted 15 at its angle to rock in the casing and being removable and replaceable through the open rear side of the casing upon axial movement of the lever, one arm of the lever extending through one of the openings to the outside 20 of the casing and serving as a handle and the other arm being movable into and out

of the casing through the other opening and serving as a latch and the casing being provided with a shoulder arranged to act as a barrier to partly close the rear side of one of said openings, and the arm of the lever extending through said opening being movable behind the barrier into interlocking engagement therewith when the latch is in latching position and being movable clear 25 of the barrier when the lever has been operated to move the latch arm within the casing and a spring acting on the lever to normally thrust the latch arm outwardly and said lever into interlocking engagement 30 with said barrier.

In testimony whereof, I have hereunto signed my name, at Syracuse, in the county of Onondaga, and State of New York, this 4th day of December, 1922.

EDWARD F. CHAFFEE.
